UNITED STATES PATENT OFFICE.

EMANUEL KOPRIWA, OF CHICAGO, ILLINOIS, ASSIGNOR TO E. KOPRIWA COMPANY,
OF CHICAGO, ILLINOIS, A CORPORATION OF ILLINOIS.

DESIGN FOR A STANDARD FOR LAMPS AND OTHER ARTICLES.

49,824.

Specification for Design.

Patented Oct. 31, 1916.

Application filed July 31, 1916. Serial No. 112,463. Term of patent 7 years.

To all whom it may concern:

Be it known that I, EMANUEL KOPRIWA, a citizen of the United States, residing at Chicago, in the county of Cook and State of Illinois, have invented a new, original, and ornamental Design for Standards for Lamps and other Articles, of which the following is a specification, reference being had to the accompanying drawing, forming a part thereof.

The drawing is a perspective view of a standard for a lamp or other article, showing my new design.

I claim:

The ornamental design for a standard for a lamp or other article, as shown.

EMANUEL KOPRIWA.
